UNITED STATES PATENT OFFICE.

FRANK L. ALBEN AND HAROLD A. HOUSTON, OF WILKINSBURG, PENNSYLVANIA,
ASSIGNORS TO WESTINGHOUSE ELECTRIC & MANUFACTURING COMPANY, A COR-
PORATION OF PENNSYLVANIA.

INTEGRAL CAB-FRAME STRUCTURE.

Application filed August 22, 1922. Serial No. 583,564.

To all whom it may concern:

Be it known that we, FRANK L. ALBEN, a citizen of the United States, and a resident of Wilkinsburg, in the county of Allegheny and State of Pennsylvania, and HAROLD A. HOUSTON, a citizen of the United States, and a resident of Wilkinsburg, in the county of Allegheny and State of Pennsylvania, have invented a new and useful Improvement 10 in Integral Cab-Frame Structures, of which the following is a specification.

Our invention relates to electric-railway vehicles and more especially to supporting-frame structures for vehicle bodies.

15 It is among the objects of this invention to provide an electric-locomotive-cab frame which shall be of rigid, durable and simple mechanical construction.

It is a further object of this invention to 20 provide a cab frame which shall be relatively simple and inexpensive to manufacture.

Heretofore, it has been customary practice to construct locomotive cab frames of structural parts requiring fitting, machining, 25 assembling and riveting or the like. Usually, several castings and channel members were employed to produce such a body structure, which involved considerable expense and labor.

30 Our present invention is directed to a locomotive-cab-frame structure comprising a single integral casting which is adapted to be supported upon a plurality of wheeled-truck members. The unitary structure comprising the side-frame portions, cross-ties, center bearings and aisle frames simplifies manufacture and greatly reduces the cost 35 thereof besides providing a rigid lightweight and mechanically durable construction.

40 In the accompanying drawings, constituting a part hereof and in which like reference characters designate like parts.

Figs. 1 and 2 represent fragmentary plan 45 front and rear views, respectively, of a locomotive-cab-frame structure made in accordance with this invention;

Fig. 3 is a cross-sectional view taken along the line III-III of Fig. 1, which is the preferred form of side-frame cross-section;

50 Fig. 4 is a sectional view corresponding to Fig. 3 but showing a different form of side-frame section, and

Figs. 5 and 6 are cross-sectional views

taken on lines V-V and VI-VI, respectively, of Fig. 1, but illustrating modified means for supporting the cab frame on the truck body portions. 55

Referring to Fig. 1, the casting consists of a pair of longitudinal side frames 1, having a plurality of transverse tie-rod connections 2 to reinforce them against lateral stressing and having a plurality of center-bearing plates 3 and 4 adapted to be pivotally mounted on a plurality of truck members shown in the cross-sectional views of Figs. 3 and 6. The end portions of the front and rear trucks are provided with bumpers 5 and 6, respectively. An aisle frame 7, extending parallel with the side frames 1, is secured thereto by a plurality of transversely projecting brackets 8. A hinge 31, connecting a pair of supporting trucks, is shown at the upper end of Fig. 1. 60

The center-bearing plate 3 (Figs. 2 and 6) 75 is provided with an opening 9 adapted to receive a center pin 10 which is rotatably mounted in a center bearing 11 provided in a cross-tie 12 of the supporting truck. The center-bearing plate 4 (Fig. 1) is provided 80 with an annular recess 13 (Fig. 3) adapted to receive a center pin 14 which is rotatably mounted in a split block 15 movably secured to a guide 16 constituting an integral part of the truck cross-tie 12 to provide longitudinal movement of the block with the truck. This relative longitudinal movement of the truck and cab frame is necessary, because 85 of the cording of the cab under frame when the trucks pass over a curve. 90

Referring to Fig. 3, the side frames 1 are preferably of substantially box-shape in cross-section having a longitudinal recess 18 formed therein which reduces the weight of the members to a minimum and yet provides 95 adequate strength. The side frames illustrated in Figs. 4 and 5 are of different cross-section but all of these are recessed longitudinally to combine minimum weight with maximum strength. In Fig. 3, the side frames 1 are provided with a plurality of longitudinally spaced side-bearing blocks 19 having a horizontal plane bearing surface 20 adapted to seat on correspondingly shaped bearings 21 secured to the truck cross-ties 12 which are mounted on the truck side frames 22 that are journaled to the traction wheels 23 in the usual manner. 100 105

Although it is common practice to support the cab structure on the center bearings 3 and 4, it is proposed that the side bearings 20 and 21 serve as the main supporting area, thus providing for a more uniform distribution of the load and stresses in the cab frame and the supporting-truck structure. The side frames 1 (Fig. 3) are adapted to receive a motor housing 24 having projecting seating flanges 25 which are secured thereto in a suitable manner.

Referring to Fig. 5, a cross-equalizer arm 27, pivotally mounted on one of the cross-ties 12 of the truck by an equalizer pin 28, is supported on its ends by spring-hangers to the drive springs 29 which are supported over the driving box (not shown) by saddles 30.

It will be readily seen from the above description of our invention that locomotive beds constructed in accordance therewith provide rigid and mechanically durable structures readily adapted to manufacture, with the elimination of various operations and expense heretofore necessary in semi-rigid frame structures. It will also be obvious that such unitary body support diverts thrusts and stresses from the motor-generator sets and other apparatus mounted thereon.

Although we have described a specific embodiment of our invention, it will be obvious to those skilled in the art that various changes may be made in the details of construction, as, for instance, the general design of the frames, reinforcing supports, center, side bearings and the like may be modified to suit any given condition of cab or truck design in accordance with operating requirements. The cross-sections illustrated in Figs. 3, 4, 5 and 6 may be modified in their general shape and outline to accommodate any condition of stressing or loading, and the method of mounting the bed on the supporting trucks may be accomplished in any suitable manner.

These and other changes may be made without departing from the principles herein set forth.

50 We claim as our invention:

1. A supporting frame for vehicle bodies comprising an integral casting having longitudinal side-frame, tie-rod, center-bearing and aisle-frame portions.

55 2. A supporting frame for vehicle bodies comprising an integral casting having longitudinal side-frame, transverse tie-rod, center-bearing and aisle-frame portions and having a plurality of side-bearing supports formed integral therewith.

60 3. A supporting frame for vehicle bodies comprising an integral casting having longitudinal side-frame, transverse tie-rod, center-bearing and aisle-frame portions and having a plurality of side-bearing supports

formed integral therewith, said side-frame portions being provided with longitudinal recesses.

4. A supporting frame for vehicle bodies comprising an integral casting having longitudinal side-frame, transverse tie-rod, center-bearing and aisle-frame portions and having a plurality of side-bearing supports formed integral therewith, said side-frame portions being of substantially box-shape in cross-section.

5. A supporting frame for vehicle bodies comprising an integral casting of longitudinal side-frame, transverse tie-rod, center-bearing and aisle-frame portions having a plurality of side-bearing supports formed integral therewith and said side-bearing supports constituting a plurality of longitudinally spaced surface-bearing blocks.

6. A supporting frame for vehicle bodies comprising an integral casting of longitudinal side-frame, transverse tie-rod, center-bearing and aisle-frame portions, said aisle-frame portions extending parallel with said side frames and being connected thereto by a plurality of transversely projecting brackets.

7. A supporting frame for vehicle bodies comprising an integral casting of longitudinal side-frame, transverse tie-rod, center-bearing, front and rear end-frame and aisle-frame portions, said portions being reinforced to provide a rigid bed structure.

8. A supporting frame for vehicle bodies comprising an integral casting of longitudinal side-frame, transverse tie-rod, center-bearing, front and rear end-frame, and aisle-frame portions, said portions being reinforced to provide a rigid bed structure and said side frames being of hollow construction.

9. A supporting frame for vehicle bodies comprising an integral casting of longitudinal side-frame, transverse tie-rod, center-bearing, front and rear end-frame and aisle-frame portions, said portions being reinforced to provide a rigid bed structure having a plurality of side-bearing supports formed integral therewith, said side-frame portions being provided with longitudinal recesses and said side-bearing supports constituting a plurality of longitudinally spaced surface-bearing blocks.

10. An electric locomotive cab frame comprising a supporting frame for vehicle bodies comprising an integral casting of longitudinal side-frame, transverse tie-rod, center-bearing, front and rear end-frame and aisle-frame portions, said portions being reinforced to provide a rigid bed structure.

In testimony whereof, we have hereunto subscribed our names this 5th day of August, 1922.

FRANK L. ALBEN.
HAROLD A. HOUSTON.
